PLLC(57) **CLAIM**

The ornamental design for a mobile stacking container, as shown and described.

DESCRIPTION

FIG. 1 is an upper perspective view of a mobile stacking container showing our new design.

FIG. 2 is a front view thereof;

FIG. 3 is a rear view thereof;

FIG. 4 is a side view thereof;

FIG. 5 is an opposite side view thereof;

FIG. 6 is a top view thereof;

FIG. 7 is a bottom view thereof; and,

FIG. 8 is an exploded perspective view thereof.

The features presented in broken lines represent unclaimed portions of the mobile stacking container and form no part of the claimed design.
